ATTORNEY

UNITED STATES PATENT OFFICE.

ANTHONY H. RANK, OF PHILADELPHIA, PENNSYLVANIA.

LOCOMOTIVE.

SPECIFICATION forming part of Letters Patent No. 417,586, dated December 17, 1889.

Application filed February 15, 1889. Serial No. 299,963. (No model.)

To all whom it may concern:

Be it known that I, ANTHONY H. RANK, of Philadelphia, in the county of Philadelphia and State of Pennsylvania, have invented a new and Improved Locomotive, of which the following is a full, clear, and exact description.

The object of the invention is to provide a new and improved compound locomotive which is simple and durable in construction, effective in operation, and very equally balanced.

The invention consists in certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is an elevation of my improvement. Fig. 2 is a plan view of the same with the boiler removed. Fig. 3 is a front view of the improvement with the head-gear removed. Fig. 4 is a front view of a pair of driving-wheels. Fig. 5 is a side elevation of the main frame. Fig. 6 is a side elevation of the center frame. Fig. 7 is a front view of the supporting-frame for the axle-box. Fig. 8 is a side elevation of the same. Fig. 9 is a plan view of the same, and Fig. 10 is an elevation of the crank-shaft for the valves.

The improved locomotive A is provided with two high-pressure cylinders B B' and two low-pressure cylinders C C', which latter are arranged on the sides of the high-pressure cylinders B B', respectively, as is plainly shown in Fig. 2. The cylinders B B' and C C' are placed alongside of each other, and are supported in the front end of the main frame D, of the usual construction, as is plainly shown in Fig. 5.

The low-pressure cylinders C and C' are connected by the usual means with the crank-pins E E', respectively secured on the front drive-wheels F F', respectively, both secured on the front axle G. The crank-pins E and E' are also connected by the pitmen H and H' with the crank-pins I² and I³, respectively, of the driving-wheels I and I', secured on the axle J, mounted to rotate in suitable bearings held on the main frame D. On the crank-

pins E and E' are secured the crank-arms K and K', respectively, pivotally connected by links K² with crank-arms K³ and K⁴, respectively secured on the crank-pins I² and I³ of the rear drive-wheels I and I'. This device serves to counterbalance the drive-wheels F F' and I I', as the latter are not provided with counterbalancing-weights, but have their rims made very heavy, as is plainly shown in Fig. 1.

The crank-pins E and E' of the drive-wheels F and F', respectively, stand at right angles to each other in the usual manner, and the crank-pins of the rear drive-wheels are similarly arranged. The crank-arms K and K' K³ and K⁴ extend diametrically across the center of the respective shaft G or J, as is plainly shown in Fig. 1.

The high-pressure cylinders B and B' are connected by the pitmen L and L', respectively, with the crank-disks N and N', respectively secured on the front axle G, between the side beams of the main frame D. On the axle G, between the crank-disks N and N', are secured the double eccentrics O and O', connected in the usual manner with the links P and P', actuating the crank-shafts Q and Q', respectively mounted to turn in suitable bearings on the main frame D. Each of the shafts Q and Q' is provided with a crank-arm Q², connected with the valve in the high-pressure cylinder B or B', respectively, and the said crank-shaft Q or Q' is also provided with the crank-arm Q³, extending diametrically opposite the crank-arm Q² and connected with the valve in the low-pressure cylinder C or C', respectively.

The reversing-shaft R is mounted on top of the main frame D, and is connected in the usual manner with the links P and P', being operated in the ordinary manner from the cab of the locomotive by the engineer. The axle G is mounted to turn in the outer bearings S S' and the inner bearings S² S³, secured in a rectangular frame T, mounted to slide in suitable grooves in the side beams of the main frame D. The outer bearings S and S' are also fitted to slide vertically in guideways D', formed in the main frame D, as is plainly shown in Fig. 5.

The rectangular frame T is guided at its upper part in the bracing-frames U, connected

at their forward ends to the castings of the high-pressure cylinders B and B'. The rear ends of the bracing-frames U are secured on the transverse rod V, fastened to the side beams of the main frame D.

The operation is as follows: The steam enters in the usual manner into the steam-chests of the two high-pressure cylinders B and B', so that the latter impart a rotary motion to the axle G by the connection of the pitmen L L' and the crank-disks N N'. The exhaust-steam from the high-pressure cylinders B and B' passes into the low-pressure cylinders C and C', respectively, so that the latter transmit the power of the steam to the crank-pins E and E' on the front driving-wheels F and F', secured on the axle G. The latter thus receives a second impulse from the exhaust-steam discharged by the high-pressure cylinders B and B' through the heads of the low-pressure cylinders C and C'. The rear drive-wheels I and I' are operated from the front drive-wheels F and F' in the usual manner by the respective connections. Both sets of wheels are completely balanced by the additional crank-arms K, K', K², and K³ and the connecting-links K². By the use of four cylinders the four connecting-rods, which are of great weight, balance one another. By the use of the crank-disks N and N', I counterbalance the axle G, and by using the four parallel links and beams H K² and H' K², I completely counterbalance the front and rear drive-wheels F F' and I I'.

The special arrangement of the cylinders, as shown and described, forces the locomotive to drive straight ahead, thus obviating the oscillating motion of the locomotives now in use, which oscillating motion is the source of great destruction to rails and machinery. As the drive-wheels are perfectly counterbal-

anced, I overcome the damage done by the present counterbalance-weights on the drive-wheels. The counterbalance-weight of the drive-wheels as heretofore constructed is 45 fully equalized by making the rims of the said drive-wheels very heavy, as before stated.

The center frames U and U' relieve the sectional axle G of all horizontal strain, and the frame T, supporting the axle-bearings S, S', S², and S³, relieves the axle of all vertical strain.

Having thus fully described my invention, I claim as new and desire to secure by Letters Patent—

1. In a locomotive, the combination, with the front axle and drive-wheels mounted thereon, of crank-disks mounted on the axle between the drive-wheels, and double eccentrics on the axle between the crank-disks, 60 substantially as and for the purpose set forth.

2. In a locomotive, the combination, with the front and rear wheels, each provided with a crank-pin having a crank-arm, pitmen H, connecting the crank-pins, links connecting the crank-arms, and crank-disks mounted on the axle of the front wheels between the said wheels, whereby both sets of wheels and the front axle will be balanced, substantially as described.

3. In a locomotive, the combination, with a main frame, of boxes held to slide vertically in the said frame and supporting the front axle, a rectangular frame fastened on the said boxes, and a center frame supported on the 75 said main frame and forming vertical guide-ways for the said rectangular frame, substantially as shown and described.
